SECTIONAL WARP BEAM FOR WINDING AND
DYEING WARP

Ralph R. Hall, Chicago, Ill.

Application July 25, 1932, Serial No. 624,516

5 Claims. (Cl. 8—19)

My invention relates to sectional warp beams, its general objects being those of facilitating the dyeing of warp threads, permitting the full lengths of the warp threads on the warp beam to be utilized in the weaving, and preventing a tangling of the warp threads from different sections of the warp beam.

When a dyeing of warp threads is required, it has heretofore been customary to first wind each thread separately on a cone or tube to eliminate snarls and tangles and to make the tension on various portions of the thread more nearly uniform. Then the thread on this cone is processed (by boiling it out, dyeing, washing and sizing it), after which the needed number of the dyed threads are wound from a corresponding number of such cones upon a section of the warp beam.

My present invention aims to eliminate this preliminary winding of the thread on a cone by providing a warp beam section upon which the required number of threads for the section can be wound direct from the same number of skeins or spools; and by constructing each such warp beam section so that the threads thereon can be dyed and otherwise processed after they are wound on the section. Furthermore, my invention aims to provide a spool-type warp beam section for this purpose which will readily permit an adequate penetration of the threads on such a section by the liquids used in the processing and dyeing, so as to insure an adequate initial boiling out and a substantially uniform dyeing of all of the threads on the prewound section without requiring the processing liquids to be applied under pressure.

In addition, my invention aims to provide a warp beam section with a lead-tape which will permit approximately the entire length of the threads to be used in the weaving, without interfering with the above recited processing of the threads after they are wound on such a spool-type warp beam section, and to construct the beam section so that the lead-tape can readily be attached and detached manually.

Still further and also more detailed objects will appear from the following specification and from the accompanying drawing, in which drawing Fig. 1 is a side elevation of a prewound warp-beam spool embodying my invention, with a portion of the nearer end disk of the spool broken away.

Fig. 2 is a plan view of a similarly constructed prewound spool, with both end disks complete,

but with a smaller number of corrugations in each end disk.

Fig. 3 is a central and vertical section through the prewound spool of Fig. 1 showing this as it appears when submerged within a dyeing liquid in a tank.

Fig. 4. is a fragmentary diametric section through an assemblage of my novel warp beam sections on a shaft, and including a clamp for holding these sections in contiguous positions, drawn on a smaller scale than Figs. 1 to 3.

Fig. 5 is a fragmentary end view of the same assemblage, taken from the line 5—5 of Fig. 4.

Generally speaking, I accomplish the purposes of my invention in the following manner:

(1) By perforating the ends of each spool-like warp beam section to such an extent as to permit a ready flow of liquid through them.

(2) By ribbing or corrugating the said spool ends so as to present radial ridges engaging the warp wound between these ends, together with channels through which the liquid can flow freely.

(3) By providing corrugations of uniform and counterpart spread on the end disks of these spool-like sections, so that the sections can be clamped upon the shaft of the warp beam with the corrugations in contiguous disks nesting into each other.

(4) By forming the corrugations in each disk in radial rows each disposed between two adjacent ridges of the disk, so as not to weaken the disk.

(5) By making the corrugations in each row of sizes increasing radially outward of the disk, so that the total area of the perforations will be a considerable portion of the total area of the disk.

(6) By disposing the inwardly facing ridges of each disk in a plane at right angles to the axis of the hub, so that the spacing between these inward ridges on the two disk ends of each beam section will be of uniform width.

In the illustrated embodiment of my invention, each section of my warp beam is a spool comprising a tubular hub 1 bored for slidably fitting the shaft 2 of the warp beam, and two disks 3 fastened respectively to the opposite ends of this hub. Each of these end disks is provided with perforations 4 disposed radially outward of the said hub, which perforations preferably are disposed in rows radial of the spool or warp beam section, and the disk is corrugated along radial lines between each two consecutive rows of such perforations.

The corrugations in each such end disk are preferably of uniform spread and depth, with the inwardly facing ridges 5 in a common plane P (Fig. 3) at right angles to the axis of the disk, and with 5 the outwardly facing ridges 6 in a similarly disposed common plane O.

To secure a maximum efficiency, I preferably employ perforations which decrease consecutively in size radially inward of each end disk, as 10 shown in Fig. 1, and make these perforations of such sizes that the minimum distance between each perforation and an adjacent bend line 5 is considerably less than the diameter of even the innermost or smallest perforation. By doing this 15 and also spacing the consecutive perforations relatively close to each other, I can readily cause the joint areas of these perforations to form a large portion of the area of the end disk portion which projects radially beyond the hub.

20 Each disk has a central bore 7 of approximately the same diameter as the bore 8 of the hub, and each disk is fastened to the hub 1 coaxially of the latter and with the inwardly facing ridges 5 bearing against the end of the hub. This 25 fastening may be by brads 9, supplemented by a suitable impervious cement if desired. The hub may be wood, suitably impregnated to resist the action of the processing and dyeing liquids, and each disk is desirably formed either of sheet 30 fibre or of other suitably impregnated material. Moreover, each hub desirably is preformed with two diametrically opposite longitudinal bores 10 for receiving clamping bolts 11, and also with a longitudinal surface groove 12 for housing a 35 lead-tape fastening hook 13.

To permit substantially all of the thread on each of my beam sections to be utilized, I desirably provide a lead-tape 15 fastened at one end to a loop 14 which is snapped over the hook 13, 40 this hook being entirely housed by the groove 18 in the hub so as not to prevent of smooth winding of the tape. This lead-tape preferably is made of a waterproofed and non-dye-absorbing material, and is of a width corresponding closely to the 45 length of the hub and hence also to the width W between the common planes P of the inwardly facing ridges in the end disks of the section. After the lead-tape has been tightly wound on the hub, the warp threads 17 (corresponding in number 50 to the length of the hub) are fastened to the tape end loop 16, and these threads are wound simultaneously and under a suitable tension around the lead tape. During this winding, the inward ridges of the disks serve as equivalents for 55 parallel flat disk faces in keeping the threads from snarling.

The beam section as thus wound is then immersed bodily in each of the liquids required for dyeing, or otherwise treating it, as for example by 60 immersing of such a section in the liquid 18 of Fig. 3. With the wound section thus immersed, the liquid readily flows through the disk perforations and can also flow freely through the radial channels between the disk ends and the thread, in 65 addition to reaching the periphery of the wound threads. Consequently, I can secure an adequate penetration of all of the threads by the liquid, which would be impossible with an unsectioned warp beam owing to the limited and irregular 70 depth to which liquid would penetrate the winding on the latter.

Indeed, I have found in practice that with my 75 here presented beam sections, I can effectively boil out, dye, wash and size the thread after it

has all been wound on the sections, even when using unprocessed (or so-called unfinished) thread or yarn. With the previous practice of dyeing the thread or yarn after winding the latter on cones, the thread or yarn must first be doubled, balled or split to facilitate the dyeing, all of which labor and time is eliminated by the use of my novel beam sections. Moreover, the manner in which the wound sections are manipulated during the dyeing is immaterial, Fig. 3 being merely illustrative. In practice, all sections of the beam may be wound while on a single shaft and thereafter placed loosely in a basket which is immersed in the dye tank, the dye being pumped through the tank (usually with a back and forth movement) in the usual manner.

80 After the dyeing, each wound section can be dried either in the air or in a centrifugal dryer, after which the sections are slid over the warp beam shaft 2 (as in Figs. 4 and 5) and clamped against each other by bolts 11, which bolts extend both through the longitudinal bores 10 in all of the hubs and through two pairs of clamp pieces 18 engaging opposite ends of the row of warp sections, each two clamp pieces being jointly 85 clamped to the beam shaft by bolts 19.

85 In addition to clamping the sections together so as to form a rigid unit, these bolts also prevent a relative rotation of the sections of the warp beam.

90 By arranging the lead tapes so that they can be manually detached from the respective hubs of the beam sections, I secure this important advantage over the previous practice: With such tapes permanently attached, after the heretofore customary manner, the tapes on other sections would dangle and whirl about during the winding of one section and often would catch either on threads or parts of the loom. On the other hand, with my arrangement I can start with the 95 lead tapes all detached, since each tape only needs to be attached just before winding the corresponding section. However, if all sections are to be wound with identical threads or yarn, this 100 winding of all sections can be done simultaneously by starting with all of the lead tapes attached to the hubs.

105 It will also be obvious that the proportionate dimensions of various parts of my beam sections is immaterial. For example, the lengths of the 110 hubs can be varied, as also the number of the radial flutings and the dimensions of the perforations. Hence I do not wish to be limited to the details of the construction, arrangement or mode of use of the above described embodiment, 115 since many changes might be made without departing either from the spirit of my invention or from the appended claims.

120 By forming the entire area of each end disk into substantially sharp-angled flutes, I reduce 125 the contact of each endward turn of the thread wound on any warp beam section substantially to a mere point. Also, by having this fluting extend radially inward of this disk beyond the periphery of the hub, and providing each sector-like disk portion with perforations which reach 130 approximately from the periphery of the adjacent end of the hub to the periphery of the disk, I permit an abundance of the dyeing or other processing liquid to reach all portions of the endmost turns of thread on the section excepting those which have the said mere point contacts 135 with the inner disk ridges—namely so small a contact area that the liquid permeating adjacent portions of the thread will readily be fed by 140 145 150

capillary action to these ridge-contacting portions also.

Consequently, I avoid the serious objection encountered with yarn-dyeing spools in which the 5 end disks have flat inner faces. I am aware that it has heretofore been proposed to provide such end disks with radial grooves opening toward the midlength of the spool, but such grooved end disks still afford flat sector-shaped 10 inner face parts for flatwise engagement with thread portions of considerable length; and as every weaver knows, a dyeing liquid will not penetrate sufficiently through a thread portion of any considerable length (in proportion to its 15 diameter) to insure an adequate dyeing, so that the threads which were in contact with such grooved end plates have to be sorted out and discarded afterwards because their irregular coloring would mar the appearance of the woven 20 goods.

Moreover, such grooves when of uniform width throughout their length are not adequate for enabling the liquid to reach all portions of the end- 25 ward turns of thread on a spool, when the liquid is admitted (at least to some of the grooves) from only one end of the spool. With my construction, I avoid this objection by forming each 30 annular end disk into radial flutes so as to present radial channels between each flute and the end portions of the winding of thread, each of which channels is of much greater cross-section at its 35 radially outward (or inlet) end than at its inner end. And I facilitate the entry and distribution of the dyeing liquid all the more by also providing each sector-shaped half of each flute with perforations through which the liquid can enter.

I claim as my invention:

40 1. A spool-like section for a sectional warp beam, comprising a tubular hub and two disks respectively fastened to opposite ends of the hub and each having a central perforation; each disk being provided with radial flutes presenting 45 substantially sharp-edged and radial inner ridges in a common plane with the adjacent end of the hub, and having the disk portion radially outward of the hub provided with perforations.

50 2. A warp beam section as per claim 1, in which the radial flutes in each disk are so formed that the disk also presents outer ridges in a plane spaced outwardly from the adjacent end of the hub, in which the said perforations in each disk are all spaced from both the inner 55 and outer ridges of the disk, and in which each

radial flute increases in width radially outward of the disk.

3. A spool-like section for a sectional warp beam, comprising a tubular hub, and two centrally perforated disks respectively fastened to opposite ends of the hub; each disk being provided with radial flutes presenting their inner ridges in a common plane with the adjacent end of the hub which flutes increase in width radially outward of the disk, each disk being a counterpart of the other disk and having its flutes uniformly distributed circumferentially so as to permit an interlocking of the flutes on adjacent end disks of such warp beam sections. 80

4. A spool-like section for a sectional warp beam, comprising a tubular hub, and two centrally perforated disks each having its radially inward portion fastened to and engaging one end of the hub; each disk being provided with substantially sharp-angled radial flutes presenting their inner ridges in a common plane with the adjacent end of the hub, and presenting their outer ridges in a common plane spaced outwardly from the adjacent end of the hub; 85

each disk portion which is radially outward of the hub and between an inner ridge and an outer ridge adjacent thereto being provided with perforations which increase in diameter radially outward of the disk, the total area of the perforations in each such disk portion being not 100 less than approximately half of the said disk portion. 105

5. A spool-like section for a sectioned warp beam, comprising a tubular and square-ended hub, and two end disks each having a central perforation of a diameter approximating the bore diameter of the said hub; each disk being provided with radial flutes presenting their inner ridges in a common plane with the adjacent end of the hub, so that each end turn of thread 110 wound on the section will have point contacts with the inner ridges of the adjacent end disk; each disk having only the inner ridges of its radially inward portion bearing against and fastened to the adjacent end face of the hub; and each disk portion which is between an inner ridge and an outer ridge adjacent thereto and radially outward of the hub being provided with a radial row of perforations extending for approximately the entire length of the said disk 115 portion, whereby the said flutes will freely admit liquid to all portions of end turns of the thread wound on the section except the thread portions having the said point contact with inner ridges of the said flutes. 120
